US0D1016109S

(12) **United States Design Patent** (10) **Patent No.:** **US D1,016,109 S**
(45) **Date of Patent:** **** Feb. 27, 2024**

(54) **SHARPENING MACHINE**

(71) Applicant: **Shenzhen Sanjing Technology Co., Ltd.**, Shenzhen (CN)

(72) Inventor: **Wen Yi**, Guangdong (CN)

(**) Term: **15 Years**

(21) Appl. No.: **35/515,305**

(22) Filed: **Aug. 12, 2022**

(80) **Hague Agreement Data**

Int. Filing Date: **Aug. 12, 2022**

Int. Reg. No.: **DM/223720**

Int. Reg. Date: **Aug. 12, 2022**

Int. Reg. Pub. Date: **Oct. 7, 2022**

(51) **LOC (14) Cl.** **15-09**

(52) **U.S. Cl.**

USPC **D15/124**

(58) **Field of Classification Search**

USPC D15/122, 124, 126, 138, 139, 140; D8/35, 62, 63, 70, 71, 91, 354

Primary Examiner — Calvin E Vansant
Assistant Examiner — Mark T. Philipps

(57) **CLAIM**

The ornamental design for a sharpening machine, as shown and described.

DESCRIPTION

1.1—front view of a sharpening machine showing my new design;

1.2—back view thereof;

1.3—left view thereof;

1.4—right view thereof;

1.5—top view thereof;

1.6—bottom view thereof; and

1.7—left front perspective view thereof.

The broken lines shown in the figures depict portions of the sharpening machine that form no part of the claimed design.

1 Claim, 7 Drawing Sheets
